UNITED STATES PATENT OFFICE.

PERRY GRAHAM, OF BLAINE, WASHINGTON.

TREE-FELLING FOOTBOARD.

1,109,749.

Specification of Letters Patent. Patented Sept. 8, 1914.

Application filed February 2, 1914. Serial No. 816,074.

To all whom it may concern:

Be it known that I, PERRY GRAHAM, a citizen of the United States, residing at Blaine, in the county of Whatcom and State of Washington, have invented a new and useful Tree-Felling Footboard, of which the following is a specification.

This invention relates to improvements in tree felling footboards.

- 10 An object of the present invention is to provide a device of the class named which may be easily and quickly secured to a tree and in which the supporting board may be moved to any angle throughout a large arc.
- 15 A further object is to provide a tree felling device which is adapted to wedgedly engage the trunk of a tree or other structures and includes a stay rod which fastens to the structure at a distance above the 20 wedge engagement of the device and necessarily holds the same in place and to which is pivotally secured a footboard for the support of the ax men.

With the foregoing and other objects in view which will appear as the description proceeds, the invention resides in the combination and arrangement of parts and in the details of construction hereinafter described and claimed, it being understood 30 that changes in the precise embodiment of the invention herein disclosed can be made within the scope of what is claimed without departing from the spirit of the invention.

In the drawing accompanying this specification and forming a part thereof, the preferred embodiment of my invention is illustrated, in which:

40 Figure 1 is a view in perspective of my improved device showing the same attached to the trunk of a tree. Fig. 2 is a vertical sectional view thereof. Fig. 3 is a detail view in perspective of the supporting board proper. Fig. 4 is a view of a somewhat modified form of stay rod to be used in connection with my improved device. Fig. 5 is a cross sectional view taken on the line 5—5 45 of Fig. 2.

Referring to the drawings in which similar reference numerals designate corresponding parts throughout the several views, a wedge 5 is provided upon its enlarged portion with a block or head 6 beneath which is a supporting bracket 7. The supporting bracket has a central portion 8 removed 55 for a purpose which will be more fully here-

inafter explained. The block or head 6 presents a broad flat outer surface against which are directed the blows for the securing of the wedge to a tree or allied structure 9. The device herein disclosed may be used for 60 felling trees or may be used with equal facility upon poles, bridge structures and the like. The block or head 6 is provided with an aperture 10 which as illustrated in Fig. 2 lies above the central opening 8 of the 65 supporting bracket. A supporting board or platform 11 is provided at its end with a bracket 12 secured thereto and which bracket is provided with an upstanding pin 13 which as illustrated in Fig. 1 is adapted 70 to project within the opening 10.

The supporting board rests upon the bracket 7 and as weight is brought to bear upon the outer extremity of the platform 11, the end is moved upward within the 75 opening 10 and the friction accompanying such force of contact prevents the accidental displacement or swinging of the supporting board. In order to positively prevent the 80 accidental displacement or swinging of the supporting board the supporting bracket 7 is serrated and the bracket 12 is also serrated as illustrated in Fig. 5. However it is to be noted that the board may be moved about the pivot or pin 13 as a center to thus 85 vary the angular adjustment of the supporting board to suit the bearing conditions as the tree is being cut or felled.

A staple or equivalent 14 is carried by the 90 upper portion of the block or head 6 and to which is hingedly secured a stay rod 15. The upper extremity of the stay rod is bent inward and provided with the sharpened blade 16 adapted to be forcibly driven into the structure 9 as illustrated in Fig. 2. A 95 somewhat modified form of stay rod is illustrated in Fig. 4 in which the dog hook 16' is pivotally secured to the upper extremity 17 of the stay rod and takes the place of the ordinary blade 16. The stay rod extends at 100 an angle to the trunk of the tree and thus securely anchors the wedge in place as it is thought will be readily appreciated from a 105 reference to the drawings. When it is desired to remove the supporting board from the block it may be accomplished by raising the outer extremity of the board which lowers the pin or pivot out of engagement with the opening 10 and allows the board with its bracket to be removed from the wedge. The 110

foregoing is rendered possible by providing the central openings 8 in the supporting bracket.

Having thus fully described my invention, 5 what I claim as new is:—

A device of the class described comprising a wedge, a head portion carried thereby, a supporting bracket projecting beneath said head provided with an apertured central portion, said head provided with an 10 opening extending therein positioned above the aperture of the supporting bracket, and

a platform provided with an upstanding pivot resting upon said supporting bracket with the pivot removably projecting within 15 the head opening.

In testimony that I claim the foregoing as my own, I have hereto affixed my signature in the presence of two witnesses.

PERRY GRAHAM.
